UNITED STATES PATENT OFFICE.

BARUCH LEVY, OF BROOKLYN, NEW YORK.

SUGAR DISPENSER.

Application filed April 26, 1928. Serial No. 272,930.

This invention relates to dispensing devices, and more particularly to such devices as are adapted for the dispensing of cubes of sugar.

5 An object of this invention is to provide a container for cube sugar which is equipped with means for dispensing cubes of sugar one at a time.

10 A further object is to the provision of a cube sugar dispensing device which may be readily disassembled so that it may be cleaned when desired.

15 These and other objects are attained by the novel construction, combination and arrangement of parts hereinafter described and shown in the accompanying drawing, constituting a material part of this disclosure and in which:

20 Fig. 1, is a cross-sectional side view of the dispensing device.

Fig. 2, is a sectional front view of the device.

Fig. 3, is a rear view of the device.

25 Referring to the drawings the cube sugar dispenser is shown to comprise a casing 6 having an aperture through which cubes of sugar may pass. A receiving cup 7 and a guard 8 are formed integral with the casing near the aperture. The casing is supported 30 by legs 9 which may be shaped in various manners for ornamental purposes.

35 Removably positioned in the casing is an inclined table 10 which has integral therewith a vertical wall 11 having an inclined portion 12. The space between the wall 11 and the casing comprising a compartment in which is slidable the yoke 13, having pivoted thereto a chute 14, the yoke being provided with a lip 15.

40 The table 10 has a central depressed portion 16, to the under side of which is attached a bracket 17 to support the rod 18 upon which is fixed a lever 19. The lever 19 is provided at its ends with rollers 20 and 21, which are 45 adapted to engage the curved end 22 of a lever 23, the latter being rotatably mounted on a fulcrum pin 24 which is supported by a bracket 25 fixed to the under side of table 10.

50 The arm 26 of the lever 23 is pivoted to a rod 27 which engages the lower surface of the yoke 13.

55 Fixed to the side walls of the yoke 13 are bent rods 28 slidable in slots 29 in the webs of the angle members 29, the latter being fixed to the wall 11 and positioned in the compartment formed by wall 11 and the cas-

ing 6. The ends of rods 28 are attached to tension springs 31 which tend to normally hold the yoke 13 in a lowered position, and the springs are also attached at 32 to the 60 wall 11.

The chute 14 is pivoted to a pin 34 attached to the yoke 13 and when the yoke is in the lowered position the outer end of the chute lies below the edge 33 of the aperture 37 in 65 the casing. The pin 34 is guided by a slot 34' in the side walls of the yoke 13.

The end of rod 18 is threaded and extends to an aperture in the casing 6, through which an internally threaded tube 35 may be passed 70 to engage the rod 18. The tube 35 carries a handle 36 by means of which the rod 18 may be rotated to rotate lever 19.

75 In operation, cubes of sugar are placed in the container and rest upon the table 10, and due to the inclination of the table the cubes of sugar naturally move downwardly in the central depressed portion 16 of the table on to the chute 14, but are prevented from passing through the aperture 37 by the edge 33. 80 When a cube of sugar is desired, the handle 36 is rotated to rotate lever 19 to depress the end 22 of lever 23 and raise the rod 27 to raise the yoke 13 and incidentally raise the lip 15 of yoke 14 to a position in alignment with the aperture 37 to thus allow a cube of sugar to 85 pass through the aperture and fall in the receiving cup 7. The springs 31 instantly lower the yoke and prevent the passage of more than one cube of sugar at a time. 90

95 A suitable cover 38 is provided for the casing and the space below the table 10 may be used for storing salt and pepper containers, and for this purpose doors 39, 40 are provided in the walls of the casing.

100 From the above description it will be seen that I have provided a dispensing device which will prevent waste of sugar and at the same time provide an attractive and sanitary article for table use.

The foregoing disclosure is to be regarded as descriptive and illustrative only, and not as restrictive or limitative of the invention, of which obviously an embodiment may be constructed including many modifications 105 without departing from the general scope herein indicated and denoted in the appended claims.

Having thus described my invention, what I claim as new and desire to secure by Letters Patent, is:

1. A sugar dispensing device comprising a

casing having an aperture in a wall thereof, an inclined table positioned in the casing, a vertical wall positioned in the casing near the aperture, a chute supported by the table, 5 a slidable yoke to which the chute is pivoted, said yoke having a lip normally below the lower edge of the aperture, a rod engaging the lower surface of the yoke, and a lever fulcrumed on the table and having the end 10 of one arm thereof connected with the rod so that the lip of the yoke will be raised to a position in alignment with the aperture when the lever is rotated.

2. A sugar dispensing device comprising a casing having an aperture in a wall thereof, 15 a chute positioned in the casing, a yoke to which the chute is pivoted, said yoke having a lip lying normally below the lower edge of the aperture, and means associated with 20 the yoke to raise the lip to a position in alignment with the aperture.

3. A sugar dispensing device for cube sugar comprising a casing having an aperture in a wall thereof, a chute positioned in the casing, 25 a yoke to which the chute is pivoted, said yoke having a lip normally lying below the lower edge of the aperture, means associated with the yoke to raise the lip of the yoke to a position in alignment with the aperture, and 30 resilient means to return the lip of the yoke to its normal position below the edge of the aperture.

4. A sugar dispensing device comprising a casing having an aperture in a wall thereof,

a chute positioned in the casing, and inclined 35 towards the aperture, a slidable yoke to which the chute is pivoted, said yoke having a lip normally lying below the lower edge of the aperture, a lever having the end of one arm thereof associated with the yoke, and means 40 to rotate the lever to cause the lip of the yoke to be raised to a position in alignment with the aperture in the casing.

5. A sugar dispensing device comprising a casing having an aperture in a wall thereof, 45 an inclined table positioned in the casing and having a central depression, a vertical wall positioned in the casing near the aperture and spaced from the wall of the casing to form a compartment, a chute positioned 50 in the depression in the table, a yoke slidably positioned in the compartment, the chute being pivotally connected to the yoke, a lip on said yoke normally lying below the lower edge of the aperture, a rod engaging the lower surface of the yoke, a lever fulcrumed on the table and having the end of one arm thereof attached to said rod, means to rotate the lever 55 to cause the rod to raise the lip of the yoke to a position in alignment with the aperture, and springs connected to the vertical wall and to the yoke to return the lip to its normal lowered position.

Signed in the city of New York, county and State of New York, this 9th day of April, 60 1928.

BARUCH LEVY.
